United States Patent Office

Des. 217,938
Patented June 30, 1970

217,938

CAMERA

Robert E. Bourke, Weston, Conn., assignor to GAF Corporation, New York, N.Y., a corporation of Delaware

Filed May 22, 1969, Ser. No. 17,275

Term of patent 14 years

Int. Cl. D16—01

U.S. Cl. D61—1

FIG. 1

FIG. 2

FIG. 3

FIG. 4

FIG. 5

FIG. 6

FIG. 7

FIG. 1 is an isometric view of a camera embodying my new design;

FIG. 2 is a front elevational view thereof;

FIG. 3 is a side elevational view thereof;

FIG. 4 is a top plan view thereof;

FIG. 5 is a back elevational view thereof;

FIG. 6 is a bottom plan view thereof; and

FIG. 7 is an elevational view of the side of the camera opposite from that depicted in FIG. 3.

I claim:

The ornamental design for a camera, substantially as shown.
